UNITED STATES PATENT OFFICE.

EMMA LANDGRAF, GEB. CARTHARIUS, OF DRESDEN, GERMANY.

GARTER.

1,395,192.

Specification of Letters Patent. Patented Oct. 25, 1921.

Application filed September 18, 1920. Serial No. 411,297.

To all whom it may concern:

Be it known that I, EMMA LANDGRAF, geb. CARTHARIUS, a citizen of the German Republic, and residing at Dresden, Germany, have 5 invented certain new and useful Improvements in Garters, of which the following is a specification.

This invention relates to an improved garter, which is represented on the accompanying drawing, in which Figures 1 and 2 are 10 side views of the same, in its disengaged and engaged position respectively, while Fig. 3 is a fragmentary sectional plan view of the same.

15 The improved garter comprises an elastic ribbon with angular end *a* and straight end *b*. In the end *a*, a plurality of button-holes *c* are provided. *d* is an elastic strap of adjustable length suspended from a corset or 20 the like and which carries on its lower end a square metal buckle *e, f* with a vertical cross-member *g* to which the end *b* of the elastic ribbon is attached, said cross-member having a knob *h* for engagement with one of 25 the button-holes *c* in the end *a* of the elastic

ribbon, the latter to be led beneath the lateral members of the square metal buckle. Thus, the metal buckle does not come in direct touch with the stocking to be fastened, so that the latter cannot be damaged by the 30 same.

What I claim, is:—

A garter comprising, in combination, an adjustable strap, a square metal buckle on one end of said strap having lateral members and a cross-member, a knob on the latter, and an elastic ribbon with one end attached to said cross-member and having a plurality of button-holes in its other end for engagement with said knob, said other end 35 to be led beneath the lateral members of said metal buckle, substantially as and for the purpose set forth.

In testimony whereof I have hereunto set my hand in the presence of two subscribing 45 witnesses.

EMMA LANDGRAF, geb. CARTHARIUS.
